(57) **CLAIM**

The ornamental design of a stadium desk, as shown and described.

DESCRIPTION

FIG. 1 is a perspective view of a first embodiment of a stadium desk according to the present invention;

FIG. 2 is a top plan view thereof;

FIG. 3 is a right side elevational view, the left side being a mirror image thereof;

FIG. 4 is a front elevational view thereof;

FIG. 5 is a rear elevational view thereof; and,

FIG. 6 is a perspective view of the stadium desk of FIG. 1 as shown in use.

Those portions of the figures in broken lines represent an example of the environment in which the designs of the present invention may be located, e.g., a desk base. The broken lines, however, form no part of the inventive design claimed herein.
